HIGH-POWER RESONANCE ABSORPTION ISOLATOR HAVING FERRITE SLAB OFFSET FROM POLEPIECES SO AS TO BE NON-UNIFORMLY MAGNETIZED

Lawrence A. Blasberg, Moorestown, N.J., and Leon J. Lader, Los Angeles, and Raymond A. Young, Inglewood, Calif., assignors to Hughes Aircraft Company, Culver City, Calif., a corporation of Delaware
 Continuation of application Ser. No. 572,176, Mar. 15, 1956. This application Jan. 16, 1961, Ser. No. 83,107
 5 Claims. (Cl. 333—24.2)

The present invention relates to microwave devices and is a continuation of copending application, Serial No. 572,176, Lawrence A. Blasberg et al., High-Power Resonance Absorption Isolator, filed March 15, 1956, now abandoned. More particularly, it relates to a nonreciprocal isolator adapted to be used in microwave transmission means to permit the passage of electromagnetic energy therethrough in one direction and to prevent the passage of such energy in the opposite direction.

In a microwave system it is customary to interconnect the various components thereof by means of reciprocal transmission means such as hollow waveguides. Due to this reciprocal nature characteristic, electromagnetic energy may be propagated through the transmission means with equal facility in either direction. Since the output power, the frequency, and the frequency stability of a microwave generator are normally dependent in some degree on the load into which it is working, it is desirable to place a nonreciprocal isolator in the otherwise reciprocal transmission means. Such an isolator should permit the free passage of electromagnetic energy propagating in the forward direction but should completely absorb energy propagating in the reverse direction.

Although isolators of a wide variety have been provided, one of the most efficient types are those employing a gyroresonant or ferrite element for absorbing the electromagnetic energy. Such a member is asymmetrically positioned in a section of waveguide so that the plane of circular polarization of the electromagnetic energy will pass therethrough. In addition, a biasing magnetic field is created in the gyroresonant or ferrite element substantially transverse to the direction of propagation and parallel to the plane of circular polarization. As a result, electromagnetic energy propagating in one direction and having a frequency equal to the gyroresonant frequency will be coupled into the electron spins and absorbed thereby.

Heretofore, it has been customary for the biasing flux field within the gyroresonant or ferrite member to be homogeneous or of uniform density. This in turn will insure the gyroresonant frequency being substantially uniform in all portions of the gyroresonant or ferrite member. Although such prior art isolator devices have been effective to absorb electromagnetic energy traveling in the reverse direction, their ability to effectively do so is confined to a narrow band of frequencies centered around the gyroresonant frequency. As the difference between the gyroresonant frequency and the frequency of the electromagnetic energy increases, the amount of isolation rapidly decreases.

It is now proposed to provide a more efficient gyroresonant isolator which will provide a higher degree of isolation over a wide band of frequencies than has heretofore been possible. More particularly, this is to be accomplished by providing an isolator in which a gyroresonant or ferrite member is disposed in a waveguide and a heterogeneous flux field extends transversely therethrough. Since the flux density of this field varies transversely of the gyroresonant or ferrite member, the gyroresonant fre-

2

quency inside of the member may be made to vary transversely thereof so as to correspond to the transverse position of the plane of circular polarization. As a result, even though the frequency of the electromagnetic energy may vary, as the plane of circular polarization moves it will always be located in the portion of the ferrite member where gyroresonance is occurring. This in turn will insure the isolator providing a high degree of isolation over a wide band of frequencies.

FIG. 1 is a schematic perspective view of an embodiment of the device of the present invention;

FIGS. 2 and 3 are cross-sectional schematic views of the device of FIG. 1;

FIG. 4 is a cross-sectional plan view of the device of FIG. 1 with dashed lines representative of the magnetic field of a wave being propagated from a generator to a load; and

FIG. 5 illustrates the magnetic field distribution in a plane transversely across the waveguide in the device of FIG. 1.

Referring now to the drawings, FIGS. 1, 2 and 3 show an embodiment of an isolator 10 which is adapted to unidirectionally attenuate energy reflected from a load so that it does not return to the microwave generator from whence it originated. The isolator 10 comprises a section 12 of conventional rectangular waveguide having flanges 14 and 16 to enable it to be inserted in the waveguide interconnecting a microwave generator with its associated load.

In accordance with a preferred embodiment of the invention, ferrite slabs 18 and 20 are disposed contiguous to opposite inner surfaces of the respective broad sides of the section 12 of rectangular waveguide intermediate the center lines and corresponding edges thereof. The ferrite slabs 18 and 20 are of the order of 70 mils thick and from one-fourth to one-half the width of the section 12 of waveguide in width. In general, the length of the ferrite slab 22 along the longitudinal axis of the waveguide is not critical and, for X-band, may be within the range of from 0.75 to 2.0 inches or longer and the edges of the slabs may be tapered, as shown, so as to minimize the standing-wave-ratio resulting from the insertion of the isolator 10 into the waveguide. Further, any ferrite material which can be made to exhibit gyroresonance throughout the desired band of frequencies within which operation is intended may be employed for the slabs 18, 20. As a practical matter, however, it is desirable to employ ferrite materials which have high resistivities so as to minimize the insertion loss in the wave propagated in the forward direction. Examples of ferrite materials which have been suitable for slabs 18, 20 are ferrites known commercially as "General Ceramic R-1" or "Ferroxube 106."

The apparatus for producing the asymmetrical magnetic field distribution across the waveguide section 12 includes pole pieces 22, 24 and permanent magnet 26. The pole pieces 22, 24 extend between the flanges 14, 16 and are inserted through apertures in the waveguide section 12 which are disposed directly opposite each other in the broad sides thereof and oriented so as to be parallel to the longitudinal axis of the waveguide. Further, the apertures are 0.150 inch wide and disposed along one side of the waveguide over the edges of ferrite slabs 18, 20 nearest the side of the waveguide. The face of each of the pole pieces 22, 24 is made flush with the respective inner surface of the broad side of waveguide section 12. In the present embodiment, the pole pieces 22, 24 are made of 0.150 inch thick "Armco" iron so as to completely fill the apertures through the waveguide, 0.125 inch of the face of each of the pole pieces 22, 24 being covered by the corresponding ferrite slab 20, 18, respectively.

The permanent magnet 26 is of the "horseshoe" type

and may, for example, be composed of a magnetic material known commercially as "Alnico V." In order to achieve the magnetic flux distribution in accordance with the present invention, the horseshoe magnet is disposed over the portion of waveguide including the center lines of the broad sides thereof so that the pole pieces of the magnet 26 are contiguous to the pole pieces 22, 24 as particularly illustrated in FIG. 2. The magnetic field distribution thus produced is represented by the characteristic 30 of FIG. 5. Referring to FIG. 5, a partial cross section of the device of FIG. 1 including the ferrite slab 20, pole piece 22, and a portion of the waveguide section 12 is shown for the purpose of referencing magnetic field intensity versus position across the waveguide.

In accordance with the present invention, the magnetic field intensity as represented by characteristic 30 must pass through or equal that intensity required to effect gyroresonance within the ferrite slabs 18, 20 along a plane where there is substantially pure circular polarization. In the present case, a plane of this type is located midway between the center lines and the respective edges

wave generator to the load, it is evident that the magnetic field presented to point A is rotating in a clockwise direction with respect to the applied static magnetic field, as viewed in the drawing. Electromagnetic energy reflected from the load would, therefore, be propagated back towards generator 14 and, accordingly, would present a magnetic field at point A that rotates in the counterclockwise direction with respect to the applied static magnetic field. In accordance with the invention, the polarity of the magnetic field produced by magnet 26 is poled so as to couple to the aforementioned magnetic field rotating in the counterclockwise direction. In addition to the characteristics of the ferrite material actually employed, the frequencies at which gyroresonance occurs is determined by the direct-current magnetic field. Inasmuch as the intensity of the magnetic field varies considerably across the ferrite slab 22, attenuation in the backward direction is effected over a broad range of frequencies.

Representative performance characteristics of an X-band rectangular waveguide resonance absorption isolator made in accordance with the present invention are tabulated below:

Waveguide height, in.	Length of device, in.	Weight of magnet used, oz.	Ferrite length, in.	Ferrite used	Peak powers used, kw.	Band width, percent	Insertion loss, db	Isolation, db	Back-to-front absorption ratio
0.500	1.75	20	1.6	106	350	15	≤ .5	≥ 20	≥ 40

of the broad sides of the waveguide. The exact location of the plane will vary as function of the frequency of the electromagnetic energy being propagated in the waveguide.

In the event that the ferrite slabs are composed of "General Ceramic R-1" or "Ferroxcube 106" ferrite material, the magnetic field intensity to effect gyroresonance in the X-band region is of the order of 4000 gauss. Also, in proceeding toward the center line from the nearest point thereto at which gyroresonance in the ferrite material is effected, the magnetic field intensity progressively decreases until the intensity at the center line is substantially less than that required to produce gyroresonance. Further, in the event that the ferrite slab should extend across the center line, the intensity of the magnetic field across the center line is made less than that required to produce gyroresonance so as not to effect bidirectional attenuation. Although the permanent magnet 26 has been shown and described in connection with the device of FIG. 1, the use of an electromagnet to establish a magnetic field in accordance with the present invention is considered to be within the scope of the teachings of the present specification. Also, it is understood that the height of the waveguide section 12 may be reduced to decrease the reluctance of the path of the magnetic flux and thus effect a concomitant decrease in the weight of the permanent magnet 26.

In operation, electromagnetic energy is propagated by waveguide, including the section 12 from a microwave generator to load in the $TE_{1,0}$ mode at a group velocity, V_g as indicated in the cross-sectional plan view of the device of FIG. 1 shown in FIG. 4. In FIG. 4, dashed lines 32, 34, 36 and 38 are representative of the field configurations of the magnetic field of the propagated wave. As generally known, these field configurations move through the waveguide at the group velocity, V_g . Thus, the actual magnetic field presented to a point such as "A" in the ferrite slab 20 is represented successively by vectors a , b , c , d , e and f . There is a plane of circular polarization that extends longitudinally of the waveguide where the vectors will rotate with uniform velocity; i.e., the energy is circularly polarized. This plane will move transversely of the waveguide as the frequency of the energy varies.

Inasmuch as the field configurations represented by dashed lines 32, 34, 36, 38 are progressing from the micro-

Typical performance characteristics of the above-mentioned 350 kw. high-power resonance absorption isolator over a 10% frequency band in the X-band region are:

- (a) A voltage standing wave ratio less than 1.09;
- 35 (b) An insertion loss of from 0.41 to 0.51 decibels with 200 kilowatts peak power input; and
- (c) Isolation of from 23 to 30 decibels with 30 kilowatts peak backward power.

The characteristics of the resonance absorption isolator have been measured as a function of temperature from -20° F. to $+400^{\circ}$ F. The insertion loss is decreased 0.3 db and the isolation 3.5 db in this temperature range. The change in resonance field strength of the ferrite geometry used is compensated by a change in field strength of the magnetic circuit with temperature. This gives a minimum of "detuning" with temperature. This minimum "detuning" is due to the similar Curie temperatures of the three ferrogmagnetic materials in the magnetic circuit. Ferroxcube 106 ferrite, Armco iron and Alnico V permanent magnet all have Curie temperatures of approximately 600° centigrade.

What is claimed is:

1. A unidirectional microwave transmission device comprising:
  - (a) a rectangular waveguide including a pair of opposite broad walls and a pair of opposite narrow walls;
  - (b) a magnet having a different pole piece adjacent each broad wall of said waveguide at a location distant from a first narrow wall of said waveguide between the center of the surfaces of the broad walls and a second narrow wall of said waveguide;
  - (c) an elongated slab of gyroresonant material disposed longitudinally within said waveguide substantially parallel to said broad walls thereof, said slab having a transverse width greater than the width of the pole pieces adjacent said waveguide, said slab extending transversely across the interior of said waveguide toward said first narrow wall from a position displaced toward said first narrow wall from the edges of the pole pieces closest to said second narrow wall.
2. A unidirectional microwave transmission device comprising:
  - (a) a rectangular waveguide including a pair of opposite broad walls and a pair of opposite narrow walls

and having substantially oppositely disposed longitudinal slots in said broad walls thereof, said slots being noncentrally disposed between said narrow walls thereof;

(b) a magnet having a different pole piece adjacent each broad wall of said waveguide and extending into the slots in said broad walls; 5

(c) and an elongated ferrite slab disposed longitudinally within said waveguide substantially parallel to said broad walls thereof, said slab extending transversely across the interior of said waveguide from said slots toward the narrow wall farthest from said slots, the transverse width of said slab being greater than the width of said pole pieces extending into said slots, said slab only partially overlaying the ends of said pole pieces disposed within said slots.

3. A unidirectional microwave transmission device comprising:

(a) a rectangular waveguide including a pair of opposite broad walls and a pair of opposite narrow walls; 20

(b) a magnet having a different pole piece adjacent each broad wall of said waveguide at a location distant from a first narrow wall of said waveguide between the center of the surfaces of the broad walls and a second narrow wall of said waveguide; 25

(c) and a pair of elongated ferrite slabs disposed longitudinally within said waveguide substantially parallel to said broad walls thereof, a different one of said slabs being adjacent each broad wall of said waveguide, said slabs extending transversely across the interior of said waveguide toward said first narrow wall from a position displaced toward said first narrow wall from the edges of the pole pieces closest to said second narrow wall. 30

4. A unidirectional microwave transmission device comprising:

(a) a rectangular waveguide including a pair of opposite broad walls and a pair of opposite narrow walls and having substantially oppositely disposed longitudinal slots in said broad walls thereof, said slots being noncentrally disposed between said narrow walls thereof; 40

(b) a magnet having a different pole piece adjacent each

broad wall of said waveguide and extending into the slots in said broad walls;

(c) and a pair of elongated slabs of gyroresonant material disposed longitudinally within said waveguide substantially parallel to said broad walls thereof, a different one of said slabs being adjacent each broad wall of said waveguide, said slabs extending transversely across the interior of said waveguide from said slots toward the narrow wall farthest from said slots, the transverse width of said slabs being greater than the width of said pole pieces extending into said slots, said slabs only partially overlaying the ends of said pole pieces disposed within said slots.

5. A unidirectional microwave transmission device comprising:

(a) a rectangular waveguide including a pair of opposite broad walls and a pair of opposite narrow walls and having substantially oppositely disposed longitudinal slots in said broad walls thereof, said slots being noncentrally disposed between said narrow walls of said waveguide;

(b) a magnet having a different pole piece adjacent each broad wall of said waveguide and extending into the slots in said broad walls;

(c) and a pair of elongated ferrite slabs disposed longitudinally within said waveguide substantially parallel to said broad walls thereof, a different one of said slabs being adjacent each broad wall of said waveguide, said slabs extending transversely across the interior of said waveguide from said slots toward the narrow wall farthest from said slots, the transverse width of said slabs being greater than the width of said pole pieces extending into said slots, said slabs only partially overlaying the ends of said pole pieces disposed in said slots.
